UNITED STATES PATENT OFFICE.

ELMER H. PACKARD, OF OMAHA, NEBRASKA.

RADIATOR-VALVE.

No. 823,632.

Specification of Letters Patent.

Patented June 19, 1906.

Application filed September 12, 1905. Serial No. 278,147.

To all whom it may concern:

Be it known that I, ELMER H. PACKARD, a citizen of the United States, residing at Omaha, in the county of Douglas and State 5 of Nebraska, have invented a new and useful Radiator-Valve, of which the following is a specification.

This invention relates to automatic air and vacuum valves for attachment to steam-radiators and similar structures for controlling the flow of steam and air therethrough, and has for its object to improve the construction and increase the efficiency of devices of this character.

With these and other objects in view, which will appear as the nature of the invention is better understood, the same consists in certain novel features of construction, as hereinafter fully described and claimed.

In the accompanying drawing, forming a part of this specification, and in which corresponding parts are denoted by like designating characters, is illustrated the preferred form of embodiment of the invention capable 25 of carrying the same into practical operation.

In the drawing the figure is a sectional elevation of the improved device applied.

The improved device consists of a casing or shell 10, having a contracted upper end or 30 neck 11 externally or internally threaded and with a closure 12 screwed upon the bottom of the casing 10 and provided with a stud 14, extending upwardly therefrom into the interior of the casing. The casing or shell 10 is also provided with a nipple 15, extending 35 from one side intermediate the ends for coupling to the radiator, a portion of which is indicated at 16, the connection being made where the air-valve is usually located.

Fitting into the contracted neck 11 is a 40 threaded plug 17, provided with a wrench-head 18, by which the plug may be inserted and removed and also to enable the plug to be readily adjusted longitudinally of the casing and its neck. The plug 17 is provided 45 with a central aperture or port 19, merging into a valve-seat 20 at the lower end and leading at the upper end into transverse apertures 21 in the wrench-head 18. The neck 50 portion 11 of the casing or shell 10 is provided with a cap member 22, having an internal valve-seat 23 and transverse escape-apertures 24 above the valve-seat, with a valve 25 bearing upon the seat 23. Access to the 55 seat 23 is provided by means of a threaded plug 26.

Disposed within the casing or shell 10 is an interior casing 27 somewhat smaller than the outer shell and with flexible metal ends 28 29. The lower flexible end 29 bears upon the plug 60 14, and a valve 30 is attached to the upper flexible end 28 for seating in the valve-seat 20. The inner casing 27 is designed to contain a liquid, such as ether or the like, which will vaporize and expand under a low temperature, the liquid being indicated by the dotted lines at 31.

Inserted into the shell or casing 10 and leading thence into the radiator-tube 16 through the nipple 15 is a drainage-tube 32, 70 the terminal of the tube within the shell 10 being enlarged, as at 33, while the terminal 34 within the radiator-tube 16 extends below the terminal 33, whereby a siphon structure is provided which operates to effectually 75 drain the device of any accumulations of water of condensation. By enlarging the intake end of the drainage-tube 32, as at 33, the pressure will cause the tube to fill more quickly when there are accumulations of condensation within the casing, and thus create a siphon, which will continue to flow as long as any water remains in the casing.

With a device thus constructed and applied the operation is as follows: So long as 85 there is no steam-pressure or heat therefrom within the radiator or the attachments thereto the element 31 will remain in liquid form and with the flexible ends 28 29 of the casing 27 collapsed and the valve 30 unseated. 90 When steam is turned on, the air within the radiator is expelled through the nipple 15 and thence through the port 19 and escape-apertures 21, and overcoming the gravity of the valve 25, escapes through the apertures 24. If the air-pressure thus escaping is less than the slight weight of the valve 25, the outside pressure will close the valve and prevent the entrance of air to the device or cause a vacuum therein which materially accelerates the action. When the heat of the steam has increased sufficiently to effect vaporization of the element 31, the latter in expanding elevates the casing 27 by expanding the bottom member 29 against the stud 14 105 and at the same time expands the top member 28, and thus causes the valve 30 to close the port 20 and shut off the further outflow and effectually obviates the waste of steam. The steam will thus be retained in the radiator members where its presence is required, as will be obvious.

The device is simple in construction, readily applicable to any apparatus employing steam, and operates effectually and automatically for the purposes described.

5 It will be noted that the nipple 15 is located intermediate the ends of the casing 10, so that the entering steam strikes the inner casing upon the side and obviates the tendency of the steam to elevate the casing and 10 cause the valve to close prematurely. This is an important feature of the invention and materially increases the efficiency of the invention.

Having thus described the invention, what 15 is claimed is—

1. In a device of the class described, an outer shell having an intermediate inlet and with a contracted upper portion interiorly threaded and with a detachable closure at the 20 lower end provided with a stud extending into the shell, a threaded plug engaging said threaded contracted portion and provided with a wrench-head upon the upper part having transverse escape-apertures and with a 25 vertical aperture intersecting said escape-apertures, the lower end of said vertical aperture expanded into a valve-seat, and a casing disposed in said shell and provided with expansible ends and containing a vaporizable 30 element, one of said expansible ends bearing upon said stud and the other of said expansible ends carrying a valve for engagement

with said valve-seat when the vaporizable element is subjected to heat and expands said ends.

2. In a device of the class described, an outer shell having an intermediate inlet and with a contracted upper portion interiorly threaded and with a detachable closure at the lower end provided with a stud extending 35 into the shell, a threaded plug engaging said threaded contracted portion and provided with a wrench-head upon the upper part having transverse escape-apertures and with a vertical aperture expanded into a valve-seat, 40 a casing disposed in said shell and provided with expansible ends and containing a vaporizable element one of said ends bearing upon said stud and the other of said ends carrying a valve for engagement with said valve-seat when the vaporizable element is subjected to heat and expands said ends, a cap 45 engaging the exteriorly-threaded terminal of said contracted portion and provided with an internal valve-seat and with transverse discharge-apertures, and a valve seated upon 50 said valve-seat.

In testimony that I claim the foregoing as my own I have hereto affixed my signature in the presence of two witnesses.

ELMER H. PACKARD.
